CLAIM

We claim the ornamental design for an electric scooter with foot brake, as shown and described.

DESCRIPTION

FIG. 1 is a perspective view of an electric scooter with foot brake embodying the invention.

FIG. 2 is a left side elevation view of an electric scooter with foot brake shown in FIG. 1.

FIG. 3 is a right side elevation view of an electric scooter with foot brake shown in FIG. 1.

FIG. 4 is a front elevation view of an electric scooter with foot brake shown in FIG. 1.

FIG. 5 is a rear elevation view of an electric scooter with foot brake shown in FIG. 1.

FIG. 6 is a top plan view of an electric scooter with foot brake shown in FIG. 1; and,

FIG. 7 is a bottom plan view of an electric scooter with foot brake shown in FIG. 1.

The broken lines shown in the drawings illustrate portions of the electric scooter with foot brake that forms no part of the claimed design.
